CLAIM

The ornamental design for a salt ore aromatherapy machine, as shown and described.

DESCRIPTION

FIG. 1 is a top, front perspective view of a salt ore aromatherapy machine design showing my new design.

FIG. 2 is a front view of a salt ore aromatherapy machine.

FIG. 3 is a rear view of a salt ore aromatherapy machine.

FIG. 4 is a left side view of a salt ore aromatherapy machine.

FIG. 5 is a right side view of a salt ore aromatherapy machine.

FIG. 6 is a top view of a salt ore aromatherapy machine.

FIG. 7 is a bottom view of a salt ore aromatherapy machine; and,

FIG. 8 is a bottom, rear perspective view of a salt ore aromatherapy machine.

The broken lines shown in the figures are for the purpose of illustrating portions of the salt ore aromatherapy machine and form no part of the claimed design.
